(57) CLAIM

The ornamental design for a clear pantiliner, as shown and described.

DESCRIPTION

FIG. 1 is a planar view of a clear pantiliner; and,

FIG. 2 is a planar view of an alternative embodiment of the clear pantiliner.

The surfaces not shown of the clear pantiliner form no part of the claimed design. The broken line shown in FIGS. 1 and 2 is for illustrative purposes only and forms no part of the claimed design.
